(57) **CLAIM**

The ornamental design for a wireless communication router, as shown and described.

DESCRIPTION

FIG. 1 is a top view of a wireless communication router illustrating my new design;

FIG. 2 is a front view thereof;

FIG. 3 is a rear view thereof;

FIG. 4 is a bottom view thereof;

FIG. 5 is a left side view thereof;

FIG. 6 is a right side view thereof;

FIG. 7 is a front perspective view thereof; and,

FIG. 8 is another front perspective view thereof.

The broken lines immediately adjacent the shaded areas represent the bounds of the claimed design while all other broken lines are directed to environment and are for illustrative purposes only; the broken lines form no part of the claimed design. In addition the unshaded surfaces directly adjoining the solid claimed edge in FIG. 3 surrounding the broken lines and the unshaded surface adjoining the solid claimed edge in FIG. 4 surrounding the broken lines form no part of the claimed design.
